Des. 925

Thomas Barry, of New York, N. Y.
Letters Patent No. 925. Dated Aug. 25, 1857.

The schedule referred to in these Letters Patent, and making part of the same.

Des. 925.

Be it known that I, Thomas Barry, of the City and State of New York, have produced a new and original design for the plates of a Stove, known as the Polar Stove; And I declare that the annexed delineations forming part of this specification, are accurate representations of the said plates, which are combined to form said Stove, with their ornamental parts; the side and back plates not represented being symmetrically similar to those represented.

What I claim and desire to secure by Letters Patent, as my production, is the combination and arrangement of Ornamental figures & forms represented in the accompanying drawings, forming together the ornamental design for the plates of a Stove.
